UNITED STATES PATENT OFFICE.

WILLIAM H. RICHARDS AND ALBERT E. KEUHNE, OF PHILADELPHIA, PENNSYLVANIA.

DESIGN FOR A CLOCK-CASE.

No. 39,884.

Specification for Design.

Patented March 16, 1909.

Application filed November 30, 1908. Serial No. 465,453. Term of patent 7 years.

To all whom it may concern:

Be it known that we, WILLIAM H. RICHARDS and ALBERT E. KEUHNE, citizens of the United States, residing at Philadelphia, in the county of Philadelphia and State of Pennsylvania, (whose post-office address is 1920 Arch street, Philadelphia,) have invented a new, original, and ornamental Design for a Clock-Case, of which the following is a specification, reference being had to the accompanying drawing, forming a part thereof.

The figure is an elevation of a clock case showing our new design.

We claim:

The ornamental design for clock case, as shown.

WILLIAM H. RICHARDS.
ALBERT E. KEUHNE.
